STEREOTYPE PLATE CASTING MACHINE

William F. Huck, Richmond Hill, N. Y., assignor,
by mesne assignments, to R. Hoe & Co., Inc.,
New York, N. Y., a corporation of New York

Application June 11, 1932, Serial No 616,653

24 Claims. (Cl. 22—2)

This invention relates to certain improvements in plate casting machines for casting printing plates and especially curved stereotype printing plates, and to a method of casting such plates.

5 The invention has for its especial object the production of an organized machine for casting printing plates and particularly curved stereotype plates without a riser or a tail-piece, so that plates are produced ready for the press except for 10 an interior shaving operation which may be necessary in some instances due to various reasons, as for instance an irregularity in the thickness of the mat or matrix from which the plates are cast.

A further object of the invention is to produce 15 such an organized machine in which the cast plate is delivered from the casting mechanism to a delivery by which it may be moved to any desired point in the press-room.

It is a further object of the invention to so conduct the casting operation, that is, to so conduct 20 the supply of metal to the mold that the air in the mold is driven out therefrom by the advancing metal which forms the cast plate, so that such air is not forced back through the metal, and the 25 formation of air holes which produce a weakened or porous plate is prevented.

A further object of the invention is to improve 30 the general construction and arrangement of the mechanisms making up the casting apparatus and to produce a casting apparatus of few parts and simple form, and in which the parts are easily accessible for adjustment, repair, or any other necessary or desired reasons.

Generally speaking, casting mechanism embodying the invention will include a stationary core, a movable back or cover, spaced apart to 35 form a casting chamber between them, these parts being preferably arranged in a horizontal position when casting, and means for supplying metal to the interior of the casting chamber at 40 a point between the side edges thereof so that as the metal is supplied to the casting chamber it will rise in the chamber on each side, forcing the air in the casting chamber outwardly ahead of the 45 metal. Such casting mechanism will also preferably include means for swinging the back or cover away from the core in combination with mechanism arranged to positively seize and remove a cast plate from the back after the latter has been 50 removed from the core, such means also acting to transfer the plate to a suitable delivery.

One construction for effecting the objects of the invention is shown in the accompanying drawings, but it will be understood, however, that this 55 showing is illustrative only of a machine suitable

for the purposes intended, and that the specific construction and arrangement of the parts of the machine shown may be varied without departing from the invention.

In these drawings,—
5 Figure 1 is an end elevation, partly broken away, of the casting mechanism embodying the invention;

Figure 2 is a side elevation, partly broken away and partly in section, of the mechanism shown 10 in Figure 1 looking in the direction of arrow 2 of that figure;

Figure 3 is a top or plan view, partly in section, showing the bottom of the melting pot and associated parts, the view being taken in the direction 15 of arrow 3 of Figure 4;

Figure 4 is an enlarged detail view, partly in section, of the casting mechanism shown in the preceding figures, the view being taken looking 20 in the direction of arrow 4 of Figure 3;

Figure 5 is a vertical cross-sectional view of 25 the casting mechanism, the view being taken on line 5—5 of Figure 3;

Figure 6 is a central sectional view of one end 30 of the casting mechanism, the view being taken on line 6—6 of Figure 4 looking in the direction of arrows 6 of that figure;

Figure 7 is a detail end view, partly broken away, showing the mechanism for holding the mat or matrix and operating the side gauges when removing a plate, the view being taken in the direction of arrow 7 of Figure 4;

Figure 8 is a detail vertical view, on an enlarged scale and partly in section, of part of the construction shown in Figure 1, showing the position of the back or cover of the casting box and associated parts during the removal of a plate, looking in the direction of arrow 8 of Figure 2;

Figure 9 is a detail sectional view showing the mechanism for operating the plate clamps, the 40 view being taken in the direction of arrow 9 of Figure 1;

Figure 10 is a detail sectional view of one of the head gauges and the means by which it is mounted, the view being taken looking in the 45 direction of arrow 10 of Figure 4;

Figure 11 is a detail sectional view of the mat or matrix holding and side gauge devices, the view being taken looking in the direction of arrow 50 11 of Figure 7;

Figure 12 is a broken away more or less diagrammatic view, and

Figure 13 is a detail sectional view of one of the mechanisms for automatically operating the 55

various parts of the casting mechanism shown in the preceding figures.

Referring now to these drawings, the parts of the mechanism may be supported in main side framing of any suitable construction, marked 1, 2. These side frames support a melting pot, indicated by the numeral 3, this melting pot being supported loosely in the framing so as to permit a movement thereof due to the expansion 10 of the pot, a convenient means being that illustrated in which the pot is shown as formed with brackets 4 secured to the framing by spring rod constructions, indicated at 5 in Figures 1 and 2, these springs providing the desired resilient 15 mounting.

This melting pot may be of any suitable configuration, but in the best constructions, for reasons hereinafter referred to, this pot will be what may be termed hopper-shaped, having a V-shaped discharge, formed by a pouring spout indicated at 6, as shown in dotted lines in Figure 1 and section lines in Figure 5, the walls of this spout converging, as shown in Figure 5, to form a relatively narrow discharge outlet, indicated at 7. In the best constructions, means located in the pot will be provided for keeping the metal in a desired state of fluidity, such means being of any desired character, as a plurality of electric heating units, marked 8 in Figures 1 and 2.

This metal pot is supported at a relatively high elevation above the casting chamber, as compared with the usual plate casting machines, and the pouring opening 7 and the casting chamber are arranged closely adjacent so that the hydrostatic pressure of the metal in the pot is utilized to completely fill the casting chamber, a valve mechanism, hereinafter referred to, being used to fill the mold and to cut off the metal close to the inside surface of the plate when the valve is closed.

The casting mechanism includes in the particular construction shown a concave back or cover 9, which may be provided with channels 10 for a cooling fluid for cooling the mold. The other member of the casting mechanism is a core 12 which may also be provided with channels 13 for cooling purposes. The core in the particular construction illustrated is stationary, 50 and the back or cover is movable relatively to this core, as hereinafter referred to, a space being left between them forming a casting chamber into which the metal is supplied to cast a plate, this member being indicated at 14 in Figure 1.

In accordance with the invention, the metal is supplied from the pot to this casting chamber at a point between its side or straight edges, so that the metal spreads in opposite directions in 60 the mold chamber and acts to force out any air that may be contained therein. Thus this air is not returned through the metal, with the result that a substantially non-porous stronger plate is produced. Ordinary air leakage through 65 the parts of the mold may be sufficient for this expelling of the air, but if desired exits for this air may be provided, shown as small apertures, indicated at 15 and best shown in Figure 5, these exits 15 being formed in the side gauges 70 hereinafter referred to.

This distribution of the metal in the mold chamber may be effected in various ways, but in the particular construction shown the constricted portion 6 of the bottom of the melting 75 pot enters the back of the core, which in the

particular construction shown is semi-cylindrical at a point approximately centrally thereof, as clearly shown in Figures 1 and 5, so that the casting chamber is divided approximately in half, the metal spreading substantially equally from each side of the pouring spout.

Means are provided for controlling the flow of metal to the casting chamber. While these means may vary somewhat in construction, they will, however, include a valve mechanism by 10 which the bottom of the pouring spout 6 may be opened and closed at suitable times, being open for casting of the plate and closed to permit the removal of a plate. While the particular structure of this valve mechanism may be somewhat varied, as illustrated, the bottom of the core 12 is cut out centrally widthwise, and in this cut out portion is inserted what may be termed a controller plate 16, best shown in Figure 5, which, as shown in Figure 6, is provided 20 with a plurality of pouring openings 17, a sufficient number of these openings being arranged in the plate to admit the desired amount of metal to the casting chamber. These pouring openings are controlled by a valve mechanism 25 which, in the particular construction shown, is a slide valve, though it will be understood that other types of valves, such as spring poppet valves, with suitable operating mechanism may be used if desired. Referring, however, to the 30 particular construction shown, there is provided a slide valve in the form of a bar 18, see Figure 5, having a plurality of constricted pouring openings 19, see Figure 6, the bottom of these openings being approximately the size of 35 the pouring openings 17 in the core before referred to. This bar has a sliding movement in the plate 16, this plate being formed with shoulders 20, forming lower tracks on which the valve bar may slide. The lower edge of the valve 40 bar around the pouring openings has a tight fit with the portion of the plate with which it contacts, so as to prevent leakage of metal between the plate and the lower edge of the bar. Similarly, the upper edge 21 of the bar has a tight 45 fit against the under surface of the sides of the pouring spout 6 of the pot, as indicated at 22 in Figure 5.

In the best constructions, means are provided for compensating for any expansion in the parts, 50 due to the heat of the metal, so that the valve mechanism will not stick but will operate freely under all working conditions. While means for effecting this may be somewhat varied, in the particular construction illustrated the core is 55 supported from the metal pot 3, this pot, as shown in Figure 5, being provided with a flange 23 and the core being supported from this flange by a spring rod construction 24, the springs permitting movement of the core as it expands 60 and contracts due to the varying heat of the metal, these springs being tensioned to maintain the desired pressure between the core and the surface of the valve bar.

This valve bar may be operated in any suitable manner, but in the particular construction illustrated it is connected to a cylinder 25 (see Figure 6), having a piston 26 to which fluid, under pressure, may be supplied from any suitable source, not shown, by means of a pipe 27, 70 as shown at the right side of Figure 6.

This cylinder may be supported in any suitable manner, but it is preferably supported so as to partake of the adjusting movement of the core above referred to, provided to compensate 75

for the expansion or contraction in the parts. As shown, the cylinder is provided with a flange 23 and is secured by means of bolts 29 to a frame member 30, which in turn is secured to the core 5 by means of bolts 31 (Figure 3). This inner frame 30 is a strengthening frame for the parts and is supported so as to have a vertical movement to permit the adjusting movement of the core, before referred to. This inner frame is 10 provided, as shown in dotted lines in Figure 5, with a slot or opening 32 in which slides a block 33, see Figure 6, which is secured to the melting pot 3 by bolts 34. In the same slot slides a second block 35, which is bolted to one of the 15 main frames, before referred to, by bolts 36. The spout portion 6 of the melting pot is also secured to the bottom of the pot 3 by means of bolts 37 screwed into the flange 23, before referred to, the spout member 6 being provided 20 with a flange 38 to enable this to be done. It will be seen with this construction that the core, the strengthening frame, and the mechanism for operating the slide valve may also partake of a limited movement due to the expansion and contraction of the parts. Of course, it will be understood that the cylinder 25 and associated parts will be duplicated on the other side of the casting apparatus so as to effect a reciprocating movement of the valve bar. This mechanism, 25 however, is identical to that described and a showing has been omitted for the sake of clearness.

It will be understood that a printing plate, marked 14, is cast in the casting chamber between the core and the cover, this plate in the particular construction shown being a curved or semi-cylindrical stereotype printing plate and, in accordance with the usual practice, the impression surface of this plate is formed by the 30 usual matrix or mat. Constructions embodying the invention will include means by which this mat is held in place in the casting chamber, and means by which the mat may be freed from the plate when a cast plate is to be removed. It 35 will also be understood that head gauges are provided by which a bevel, indicated at B in Figure 9, is formed on the curved edges of the plate, this bevel being provided to cooperate with the usual plate clamps on the form cylinder of the press to lock the plate in place on the cylinder, the straight edges of the plates being formed by the side bars forming a part of the matrix holding devices.

While various means may be provided for positioning the matrix and cooperating the head gauges, that illustrated is a convenient one and will now be described.

Referring to Figures 5, 7, and 11, it will be understood that the matrix is held in the concave portion or cover of the mold. In the particular construction illustrated the edges of the matrix are held by a pair of pivoted jaw members 39, 40, generally shown in Figure 8. The specific arrangement of these members may be somewhat varied, but as shown these jaw members include a lower member 41 and an upper member 42 having a sliding engagement with the lower member. The lower member is supported on arms 43 loosely mounted on a rock-shaft 44 which extends across the machine, as shown in Figure 7. The upper jaw 42 is held in place on the lower jaw 41 by a set screw 45 having a flanged head, and the upper jaw is provided with a recess 46 so that this upper jaw 42 may have a sliding movement relatively to

the screw 45 and the lower jaw 41, to clamp the upper edge of the matrix, indicated by M, in place. It will be understood that the arms 43 are supported from the walls of the cover or base 9, before referred to, and as clearly 5 shown in Figures 7 and 11. The required pressure for locking the jaws into holding relation with the matrix is afforded by a spring 47 which is preferably centrally arranged and engages a pair of fingers 48, 49 loosely mounted on the 10 shaft 44, before referred to. These fingers pass through clearance holes 50 in the lower jaw members 41, as shown in Figure 5, and engage in the upper members 42. The spring also engages an arm 51 loosely mounted on the shaft 15 44, this arm forming an abutment for the spring 47. This spring acts to hold the two jaw members in locking relation with the matrix M. It will, of course, be understood that a pair of the matrix clamps is provided on each side of the 20 mold.

Other springs, 52, 53, connected to the lower jaw members 41 and to fixed members 52', 53', act to rock the shaft 44 to hold the jaws as a whole in casting position, as shown in Figure 11. 25

After the plate has been cast, means are provided for moving the back or cover away from the core to release the plate and to deliver the plate from the cover, it being understood that as the mold is opened the plate and matrix move 30 away from the core with the cover. While these means may vary within certain limits, in the particular construction shown this movement is a swinging movement, the back or cover being 35 swung away to one side or the other of the core. In the particular construction illustrated, the cover is carried in a pair of swinging arms 54, 55, see Figure 2, on a rock-shaft 56 extending across the machine. This shaft at one end, see Figure 2, is provided with a sector 57 which engages with 40 a rack 58 connected at each end with a pair of pistons 59, 60, which operate in cylinders 61, 62 suitably supported in the main frame of the machine. These pistons are operated in any suitable manner, as by fluid pressure supplied from 45 any suitable source, not shown. The fluid pressure, of course, may be controlled in any suitable manner, either through a manual control or suitable automatic devices hereinafter referred to. The movement of the pistons causes the 50 cover to move from the casting position, shown in dotted lines at the right hand side of Figure 1, to the delivery position, shown in full lines at the left hand side of Figure 1 and more in detail in Figure 8. As the cover moves from casting to 55 delivery position, means are provided for causing the side gauges and matrix clamps to partially move away from the plate, as shown in Figure 8, and to move the head gauges to clear them from the plate, so that the plate can be re- 60 moved from the cover as hereinafter referred to.

Referring first to the mechanism for operating the side gauges and matrix clamps, this may be varied, of course, within certain limits. As illustrated, however, as the cover moves to the delivery 65 position shown in Figures 1 and 8, it passes between a pair of lever arms 63, 64, which are carried on a shaft 65 extending across the machine. These lever arms 63, 64, carry upper and lower cams 66, 67 which engage cam rolls 68, 69 on lever 70 arms 70, 71 carried on short shafts 72, 73, see Figure 7, these shafts being provided on both sides of the mechanism, as shown in Figure 7, and above and below the back or cover when it is 75 in delivery position, as shown in Figure 8, one of

the lower shafts being shown in Figure 8 and marked 73. These short shafts are provided with gear segments 75 loosely mounted thereon, which mesh with corresponding segments 76 on the 5 lower jaw member 41, before referred to. Positioned on the short shafts 72, 73 are springs 77, these springs being more heavily tensioned than the springs 52, before referred to, which are positioned on the shaft 44. The lever arms 63, 64 10 are employed to remove the plate from the mold and deposit it on a delivery mechanism. When they swing downward with the plate as will be hereinafter described, the edge of the plate contacts with the jaw members 39, 40 and starts to 15 swing the jaw members around the shaft 44. As the plate continues its outward movement through the action of the segments 75, 76, the jaw members are given a further swinging movement around their pivoted shaft 44 to the position shown in Figure 8, in which position they 20 are maintained by the heavy springs 77 until the plate has passed by them and the cam rolls 68 have rolled off the cam 66, whereupon the jaw members are returned to the closed position 25 shown in Figure 11 by the springs 52. It, of course, will be understood that the locking jaws being held in the position shown in Figure 8, the continued movement of the plate toward the right, as shown in that figure, will peel the 30 matrix from the plate, and upon the return of the locking jaws to normal position the mat will be in position for a succeeding cast.

The mechanism by which the plate is removed from the back or cover may, of course, vary in 35 construction. In the particular devices employed for accomplishing this, however, there is provided a pair of grippers for gripping the curved edges of the plate. In the particular construction shown, the lever arms 63, 64 carry a pair of 40 clips 78, 79, see Figure 2 and shown in detail in Figure 9. Each of these clips is mounted to slide in a boss 80 formed on the lever arms 63, 64, before referred to, and each clip is provided with a groove 81 dimensioned to receive the bevelled 45 edge of the plate. These clips may be given a sliding movement in the boss in any suitable manner. In the particular construction shown the boss is recessed, as shown at 82, to receive the stem of a piston 83, which acts against a 50 spring 84. This piston is operated by fluid pressure in any suitable manner, not shown, through flexible pipe connections 85, shown in Figure 2.

It will be understood that the plate is cast with the head and tail bevelled by the head gauges so 55 as to fit the end clamps on the press, and in removing a plate from the casting mechanism it is necessary that the gauges by which this bevel is produced, and which may be called head gauges, be moved out of the way so that the back or 60 cover with the plate may be removed from the core. While this may be effected in various ways, in the particular construction illustrated, see Figures 3 and 6, which show the gauges at each 65 end of the machine, and Figure 10 which shows one of the gauges in detail. These gauges are in the form of sliding plates, marked 86, Figure 6 and Figure 3. These gauge plates, as clearly shown in Figure 10, are provided with a bevelled surface 88 and are given a sliding movement so 70 that they will clear the bevel on the edge of the plate when the plate is being removed from the core. These gauges may be operated to have this sliding movement in any suitable manner. As shown, see Figure 10, the gauge is fastened, by screws 89, to a slide 90 which is provided with an

eye 91, this construction being duplicated on each side of the machine, as shown in Figure 3. These eyes are secured in one end of links 92, the other end of these links being carried on lever arms 93, the other ends of these lever arms being mounted 5 on a rock-shaft 94 extending across the machine.

This rock-shaft is provided with an arm 95, Figure 6, one end of which is connected to a spring 96, which normally acts to hold the parts 10 in closed position. The arm 95 is actuated against the spring 96 to open or to move the slides out of engagement with the plates by means of a plunger 97 operating in a cylinder 98 carried by the casting cylinder 25, before referred to, this plunger 97 being operated through a pipe connection 15 99 from any suitable source of fluid pressure, not shown. The movement of this plunger may be controlled either manually or through automatic connections, as later referred to. It may happen under certain circumstances that the weight of 20 the locking jaws and gauges and the tension of the springs 52 are not sufficient to hold the parts in proper casting position while the cast is being made. In the best constructions, therefore, means are provided for exerting a positive pressure 25 on these parts to hold them in proper position. While these means may vary somewhat in construction, there is shown a spring rod mechanism, indicated generally by the numerals 100, 101, which act to assist the springs 52 and the 30 weight of the parts in holding the locking jaws and associated parts against the pressure of the metal in the casting chamber.

After the plate is removed from the back or 35 cover as hereinbefore referred to, it is carried by the gripping devices and the swinging lever arms 63, 64 and delivered to any suitable delivery. In the particular construction shown, the lever arms act to lower the plate onto a runway or track comprising rolls on which the straight edges of 40 the plates rest, these rollers being indicated by the numeral 102. After the plate has been deposited on the rollers, the pressure in the pistons 83 is released, thus releasing the grippers, and the gripping mechanism and the lever arms are 45 then free to swing back into receiving position for the next plate. The mechanism for operating the lever arms 63, 64 may, of course, be varied within wide limits. As shown, however, this movement is accomplished by means of a gear sector 103 50 on the end of the rock-shaft 65, before referred to. This sector is in mesh with a rack 104 connected to a pair of pistons 105, 106 operating in a cylinder 107, to which fluid pressure may be supplied in any suitable manner, as by a pipe connection 108, 55 see Figure 2.

In order that the mat or matrix may be readily removed from and inserted in the locking jaws, means are provided for releasing these locking jaws, such means being shown in the form of a 60 thumb screw 109, see Figure 5, operating a screw rod 110 against the action of the spring 47, before referred to, by the operation of which rod the jaws may be loosened to permit the insertion or removal of the mat.

In the best constructions, furthermore, it may be desirable to heat the spout 6, before referred to, to keep the metal therein at the proper degree of fluidity. Where such heating is desired, this may be readily effected by a set of electric heating units, indicated by the numerals 111, 112 and 70 as best shown in Figures 4 and 5.

Where electric or other heating devices are employed, there is provided a suitable insulating medium, indicated by 113, between such units and 75

the wall of the core, this construction keeping the spout 6 at the proper high temperature and the core at the desired low temperature.

As shown and as is usual in casting stereotype plates, these plates are provided on their inner surfaces with ribs, shown, for instance, at 114 in Figures 9 and 10, the ribs being employed to provide what may be termed a bearing on the plate cylinders.

10 In machines constructed in the preferred form, the casting operation will be so controlled that the excess of metal is cut off at the height or slightly below the height of the ribs on the plate, so that there will be no projecting parts which have to be removed by trimming or shaving to fit the plate for immediate use on the cylinder.

15 While the sequence of movement in the casting operation described may be performed manually, under some circumstances it may be desirable to do this in an automatic manner, the metal supply valve being closed at the proper time and the mold opened after the plate is set and swung to plate delivery position, the grippers operated to grip the plate, and the plate delivery arms being operated to deliver the plate and return to plate receiving position. Various constructions may be utilized for effecting this automatic operation, and a mechanism for operating one of the parts of the machine in this automatic manner is shown in Figures 12 and 13 of the drawings, it being understood that this mechanism will be duplicated for automatically operating as many parts of the casting machine described as may be desired. As these mechanisms are duplicated, however, but one has been shown in detail and will now be described.

20 Referring to Figures 12 and 13, the mechanism has been illustrated as operating the pistons 59, 60, which control the opening and closing of the casting chamber, that is, the mechanism by which the cover or back is moved away from the core to plate delivery position and then back to casting position. This mechanism includes a shaft 120 which is common to all the valve mechanisms 25 which may be used, depending upon the number of parts of the casting machine it is desired to operate automatically. This shaft is provided on one end with a gear 121 which is in mesh with a worm 122 secured to a shaft 123 which is driven 30 from any suitable prime mover, as a motor 124, this motor being controlled by any suitable switch mechanism for starting and stopping it at suitable times.

25 The specific construction of the means for automatically controlling the pressure fluid to the cylinders may, of course, be widely varied, but as shown this is a valve mechanism. This valve mechanism in the particular construction illustrated includes four valves 126, 127, 128 and 129, shown diagrammatically in Figure 12 and in detail in Figure 13. Fluid pressure is supplied through a pipe 130 and escapes through a pipe 131. Connected with this fluid pressure pipe are valve casings 132, 133 for the valves 127, 129, and 35 these valve casings, through pipes 134, 135, connect with valve casings 136, 137 for the valves 126, 128. These valves are operated in proper sequence to cause the reciprocation of the pistons 59, 60 by means of four cams mounted on the 40 shaft 120, one of these cams being shown and marked 138. This cam operates with a cam roll 139 in an arm 140 which is provided with a boss 141 which operates to open a poppet valve 142, the valve being seated by the usual spring construction 143.

It will be understood that valve 127 controls the inlet to cylinder 61 while the valve 126 controls its outlet, and similarly the valve 129 controls the inlet to cylinder 62 and the valve 128 controls its outlet.

5 With this construction and the parts in proper timed relation, the pistons 59, 60 are automatically operated to open the mold and move the back or cover thereof to plate delivery position. Similar mechanism is used for operating the 1^a pistons 105 and 107 which actuate the arms 63, 64, and also for operating the controller plate 16. Similar mechanism is also provided for operating the pistons which actuate the plate gripping device 18 and for retracting the head gauges 86. 15 However, as the plate gripping and head gauge operating devices are spring operated in one direction, only two valves are necessary to operate each of them.

20 It will also be understood that if desired, the circulation of the cooling fluid may be controlled by the same timing mechanism so that the circulation is stopped when the mold is not in operation.

25 What is claimed is:

1. In a printing plate casting machine, the combination of metal supplying means, a mold having a horizontal semi-cylindrical casting chamber, and means for supplying molten metal to the casting chamber at its lowest portion along 30 a line extending throughout the length of the chamber parallel to the axis of the casting chamber and intermediate its side edges so that the metal flows upwardly in opposite directions along paths of travel of equal length in filling the mold. 35

2. In a plate casting machine, the combination of a metal reservoir, a horizontal curved casting chamber or mold supported directly below the reservoir, and means for supplying metal to the mold at its lowest portion and intermediate its 40 side edges and curved ends so that the metal flows upwardly in opposite directions from a line substantially central of said casting chamber in filling the mold.

3. In a plate casting machine, the combination 45 of metal supplying means, a horizontal curved casting chamber comprising a core and a back, means for supplying metal to the casting chamber substantially centrally of its side edges, means for swinging the back of the mold away 50 from the core, a transfer mechanism for removing the cast plate from the back, and means for operating the transfer mechanism to deliver the plate.

4. In a plate casting and delivery mechanism, 55 the combination of a metal supplying means and a two part casting chamber or mold positioned to receive molten metal directly from the metal supplying means and capacitated to cast a curved plate, plate retaining means for holding the plate 60 to a part of the casting chamber and movable to release the plate, means for lowering a part of the chamber with the plate away from the other part, plate-conveying means, and an automatically operated transfer mechanism which operably engages the plate retaining means to release the plate from the chamber part and takes the plate from the mold and deposits said plate 65 on the plate-conveying means.

5. In a plate casting mechanism, the combination of metal supplying means, a horizontal curved casting chamber comprising a core and a back, controlling means for supplying metal to the casting chamber, means for lowering the back and cast plate away from the core, means for strip- 70 75

ping the matrix from the plate, a transfer mechanism for removing the cast plate from the back and depositing same upon conveying instrumentalities, and fluid pressure devices for actuating these mechanisms.

6. In a plate casting mechanism, the combination of metal supplying means, a horizontal curved casting chamber comprising a core and a back, controlling means for supplying metal to the casting chamber, means for lowering the back and cast plate away from the core, means for stripping the matrix from the plate, a transfer mechanism for removing the cast plate from the back, fluid pressure devices for actuating these mechanisms, and automatic means for operating the fluid pressure devices in timed sequence.

7. In a plate casting and delivery mechanism, the combination of metal supplying means, a casting chamber comprising a core and a back, means for moving the back and plate away from the core, plate retaining means carried by the back to hold the plate in the back and operable to release the plate, a transfer mechanism, plate gripping means carried by the transfer mechanism and automatically operable to grip the plate, the transfer mechanism operably engaging the plate retaining means to release the plate from the back, and means for automatically actuating the transfer mechanism to deliver the plate, said last mentioned means being effective to deposit said plate upon conveying instrumentalities.

8. In a plate casting mechanism, the combination of a metal reservoir, a horizontal curved casting chamber comprising a stationary core and a movable back located below the reservoir, means for controlling the supply of metal to the casting chamber, means actuated by a valve controlled by a piston for lowering the back with the cast plate and matrix away from the core, a transfer mechanism to which the plate is delivered, means operated by the transfer mechanism for stripping the matrix from the plate, means for operating the transfer mechanism to deliver the plate, and automatically operated fluid pressure means for causing the operation of these mechanisms in timed sequence.

9. In a plate casting mechanism, the combination of metal supplying means, a horizontal curved casting chamber comprising a stationary core and a movable back located below the metal supplying means, means for lowering the back with the cast plate away from the core, a transfer mechanism, plate gripping devices on the transfer mechanism for gripping the plate, and means for moving the transfer mechanism to deliver the plate from the back and deposit same on plate-conveying means.

10. In a mechanism adapted to cast a stereotype plate, the combination of a reservoir adapted to contain molten metal, a horizontal curved casting chamber comprising a stationary core and a movable back, a duct connecting the reservoir with ports disposed substantially along the center line of the mold, a slide valve for controlling the supply of metal to the casting chamber, and fluid pressure means for operating the valve.

11. In a plate casting machine, the combination of a reservoir adapted to contain molten metal, a spout depending therefrom having converging walls, a casting chamber comprising a core and a back, a plurality of inlet ports arranged substantially along the center line of said core, a slide valve controlling the supply of metal to the casting chamber, and means for operating the valve.

12. In a plate casting and delivery machine, the combination of metal supplying means, a casting chamber including a core and a back, the core being provided with head gauges, matrix clamps, plate retaining means and side gauges carried by the back, means for moving the back with the cast plate and matrix away from the core, means for stripping the matrix from the cast plate, a conveying mechanism, and a transfer mechanism for operably engaging the plate retaining means to release the plate and for automatically taking the plate from the back and delivering it upon the conveying mechanism.

13. In a plate casting machine, the combination of metal supplying means, a casting chamber or mold in which a plate is cast, means for separating the mold parts, means for delivering the plate from the mold, fluid pressure means for operating the parts in the stated sequence, and a common means for automatically operating the fluid pressure means.

14. In a plate casting and delivery mechanism, the combination of metal supplying means, a casting chamber, plate retaining members for holding the plate to a component of the casting chamber, means for controlling the supply of metal to the chamber, plate-conveying means, operably engaging the plate retaining means to release the plate from the chamber component and automatically removing a plate from the casting chamber to the coacting plate-conveying means, and other means for actuating the metal controlling means and the means for automatically moving the plate.

15. In a plate casting and delivery mechanism, the combination of automatically operated metal supplying means, a casting chamber, plate retaining means to hold the plate in the casting chamber and movable to release the plate, means for automatically controlling the supply of metal to the chamber, plate-conveying means, means for automatically engaging the plate retaining means to release the plate and for removing the plate from the casting chamber to the coacting plate-conveying means, and means acting to cause the automatic operation of the said means in a timed sequence.

16. In a plate casting mechanism, the combination of metal supplying means, a casting chamber communicating with said metal supplying means, plate retaining means to hold the plate in the casting chamber and movable to release the plate, instrumentalities for automatically controlling the supply of metal to the chamber, delivery means for operably engaging the plate retaining means to release the plate and for automatically removing the plate from the casting chamber and bodily lowering same away from the casting chamber, and automatic means for actuating the metal controlling instrumentalities and the delivery means in operable sequence.

17. In a printing plate casting machine, the combination of metal supplying means, a horizontal semi-cylindrical casting chamber, and means for supplying metal to the chamber along a line parallel to the axis of the casting chamber and extending throughout the length of the chamber intermediate its side edges at the lowest portion of the chamber so that the metal flows in opposite directions and upwardly from the axial line in filling the chamber.

18. In a plate casting machine, the combination of a horizontal casting chamber curving uniformly laterally and upwardly from its lowest and central portion, a valve positioned at the lowest

- and central portion of the casting chamber and extending substantially the length thereof, metal supplying means positioned above the casting chamber and extending downwardly between the laterally and upwardly curved portions of the casting chamber to the valve, the valve being constructed and arranged to supply metal along a line at the lowest and central portion of the casting chamber.
- 5 19. In a plate casting machine, the combination of metal supplying means, a casting chamber, means for controlling the supply of metal to the chamber, a conveyor, delivery means for removing the plate from the casting chamber and de-
- 10 15. 20. In a plate casting machine, the combination of a metal reservoir, a horizontal casting chamber comprising a curved core and back, a spout communicating with the metal reservoir and positioned within the core and extending substantially throughout the length of the casting chamber, a valve mechanism extending substantially throughout the length of the casting chamber and controlling the supply of metal from the reservoir through the spout to the casting chamber, and means for operating the valve mechanism.
- 15 25. 30. 35. 21. In a plate casting mechanism, a frame, a melting pot supported by the frame, a mold having a casting chamber, a valve operably interposed between the melting pot and the mold and operable to control the flow of molten metal from the melting pot into the casting chamber of the mold, and common means for yieldingly securing the mold to the melting pot and for operably securing the valve between the melting pot and the mold.
22. In a plate casting mechanism, a frame, a melting pot suitably supported by the frame, a mold including a core and a removable cover defining a casting chamber therebetween, a valve operably interposed between the melting pot and the mold core and operable to control the flow of molten metal from the melting pot into the casting chamber, and common means for yieldingly securing the mold core to the melting pot and for operably securing the valve between the melting pot and the mold core.
23. In a plate casting mechanism, a frame, a melting pot suitably supported by the frame, a spout extending from the melting pot, a mold including a core and a removable cover defining a casting chamber therebetween, a valve operably interposed between the spout and the mold core and operable to control the flow of molten metal from the melting pot into the casting chamber, and means for yieldingly securing the mold core to the melting pot and for yieldingly securing the valve in operable position between the spout and the mold core.
24. In a plate casting mechanism, a frame, a melting pot supported by the frame, a mold having a casting chamber, resilient members for yieldingly securing the mold to the melting pot to permit expansion and contraction of the components of the melting pot and mold, and a valve operably interposed between the mold and melting pot and operable to control the flow of metal from the melting pot into the casting chamber of the mold, the valve being held in operable relationship between the melting pot and mold under the tension exerted by the resilient members.

WILLIAM F. HUCK.
